CIGARETTE SERVER

George L. West, Pittsburgh, Pa., assignor to Pittsburgh Plate Glass Company, Allegheny County, Pa., a corporation of Pennsylvania

Application April 30, 1938, Serial No. 205,258

3 Claims. (Cl. 211—13)

The present invention relates to structures adapted for the serving of smoking articles and more particularly to an article for serving cigarettes, designed for domestic use.

5 A primary object of my invention is the provision of a cigarette server in which a large number of cigarettes or similar articles are so contained in individual compartments as to be readily removable at any time.

10 A second object of the invention is to provide a cigarette server which, when placed upon a table or other support, will make available an additional surface upon which various other articles may be placed.

15 Other objects and advantages of my invention will become more apparent during the course of the following detailed description of a preferred embodiment thereof.

The ordinary cigarette box or container is 20 provided with a removable lid, designed to cover completely the supply of cigarettes, and accordingly before a cigarette may be removed from the container it is necessary to remove the cover. Obviously, therefore, nothing can be placed on 25 the box and when the usual container is placed upon a table, it will occupy space which, in case the table is crowded, could be used more profitably for other purposes. Moreover, the cigarettes are so closely packed in the container that 30 it is impossible to remove one without touching a number of others. In addition the cigarettes are customarily disposed horizontally and in parallelism so that it is inconvenient for one to be selected.

35 A cigarette server constructed in accordance with the provisions of the present invention comprises a relatively flat, disc-like body, the top surface of which may be employed as a support for articles normally placed upon a table. Radial recesses are provided around the periphery of this disc and function as individual receptacles for a number of cigarettes, maintained in such position that a portion of each cigarette protrudes from the disc a distance sufficient that it 45 may be grasped and removed easily from the server.

One embodiment of my invention is shown in the accompanying drawing, wherein: Figure 1 is a plan view of a cigarette server constructed in 50 accordance with the provisions of my invention; and Figure 2 is a sectional view thereof taken substantially along the line II—II of Figure 1.

In the drawing, a circular base plate 1 of 55 opaque structural glass or other suitable material is provided with a plurality of radially dis-

posed troughs 2, regularly spaced around the periphery of the base plate and formed therein by any suitable means, as for example, grinding or sand blasting. The troughs or grooves 2 have a depth sufficient to receive cigarettes 3 and 5 are of such length as to leave portions thereof projecting outwardly. A plurality of spaced, upwardly-extending pins 4 are secured at their bases in the plate 1 and washers 5 of rubber or other resilient material are disposed upon the 10 projecting portions of the pins. A cover plate 6 of transparent glass is superposed upon the plate 1 spaced therefrom by the washers 5, and contains sockets 7 suitably disposed to engage the extending portions of the pins 4.

15 The cover plate 6 may carry upon its lower surface an appropriate design 8, applied thereto by any suitable means, as for example, by sand blasting, etching, painting, etc. By spacing the cover plate from the base plate 1, any mechanical 20 deterioration of this design will be obviated. The design 8 may be, if preferred, formed upon the upper surface of the base plate 1, in which case it will also be protected by the spaced relation of the component elements of the server. 25

In certain instances, it may be preferred that the cover plate rest directly upon the base plate. Such construction would prevent the entrance of dust or other foreign matter between the plates. Deeper sockets 7 and elimination of the washers 5 permit the desired face to face contact. 30 The cover plate may be fixed upon the pins 4 to provide a more stable article.

In the disclosed structure, wherein the cover plate engages positively the pins 4 but is not 35 fixed thereon, it will be obvious that lateral displacement of the cover plate is impossible, although the plates may be separated for cleaning. Accordingly the upper surface of the cover plate may be used to receive articles 9, such as ash 40 trays, lighters, match cases, etc. Since the troughs 2 are not long enough to contain the entire body of a cigarette, a sufficient portion thereof will extend beyond the plates to permit an easy removal of a cigarette from the server. 45 Also, in view of the fact that the recesses are radially disposed about the periphery of the base plate, sufficient room is provided for the removal of an individual cigarette from any side of the server. Often the cigarettes stored in the grooves 50 will be of a plurality of brands to meet the tastes of various individuals. The transparency of the cover plate 6 then permits a proper selection to be made.

It will at once be obvious that various modi- 55

ifications in structural details may be made without departing from the spirit of my invention or the scope of the appended claims.

What I claim is:

- 5 1. A cigarette server comprising a circular base plate of structural glass provided with radially disposed troughs regularly spaced around its periphery, vertically projecting pins positioned in the base plate, and a circular cover plate of transparent glass superposed upon the base plate, maintained in spaced relation therefrom, and engaging the pins extending from the base plate to prevent a lateral displacement of the cover plate.
- 10 15 2. A cigarette server comprising a circular base plate of opaque structural glass provided with radial grooves regularly spaced around its periphery, each groove being of a size sufficient to receive a cigarette, vertically projecting pins centrally disposed of the base plate, and a

circular cover plate of transparent glass superposed upon the base plate, maintained in spaced relation thereto and engaging the pins extending from the base plate to prevent a lateral displacement of the cover plate.

3. A cigarette server consisting of a pair of glass plates, the upper one being transparent, of approximately circular outline, secured together by pins, spacing means comprising washers of resilient material, disposed upon the pins, a design formed upon one of the juxtaposed faces of the glass plates, recesses formed at regularly spaced intervals about the periphery of at least one of the plates, each recess being of such proportions as to contain an individual cigarette with a portion thereof projecting outwardly a distance sufficient that it may be grasped and removed easily from the server.
